Primary Examiner — Garth Rademaker*Assistant Examiner* — Samantha Q Lawrence(74) *Attorney, Agent, or Firm* — Vorys, Sater, Seymour and Pease LLP; Susanne M. Hopkins; William L. Klima(57) **CLAIM**

The ornamental design for a shed and shed roof, as shown and described.

DESCRIPTION

FIG. 1 is a perspective view of a new design for a shed;

FIG. 2 is a front elevational view thereof;

FIG. 3 is a rear elevational view thereof;

FIG. 4 is a right-side elevational view thereof;

FIG. 5 is a left-side elevational view thereof; and,

FIG. 6 is a top planar view thereof.

The broken lines shown in FIGS. 1-6 illustrate portions of the shed and shed roof that form no part of the claimed design.
